UNITED STATES PATENT OFFICE

93,484

DESIGN FOR A DOORLATCH

Ralph E. Kruck, Springfield, Mass., assignor to
Westinghouse Electric & Manufacturing Com-
pany, a corporation of Pennsylvania

Application June 7, 1934, Serial No. 52,103

Term of patent 3½ years

To all whom it may concern:

Be it known that I, RALPH E. KRUCK, a citizen
of the United States, residing at Springfield, in
the county of Hampden and State of Massachu-
setts, have invented a new, original, and ornamental
Design for a Door Latch, of which the
following is a specification, reference being had
to the accompanying drawing, constituting a part
hereof.

Fig. 1 is a front view of a door latch embody-
ing my design; and,

Fig. 2 is a side view of the door latch shown in
Fig. 1.

I claim:

The ornamental design for a door latch sub-
stantially as shown.

In testimony whereof, I have hereunto sub-
scribed my name this 29th day of May, 1934.

RALPH E. KRUCK.
